N. E. MONTAGUE
CALLING CARD RECEPACLE

1,776,951

Filed Nov. 28, 1928

UNITED STATES PATENT OFFICE

NELLE EDE MONTAGUE, OF SAN ANGELO, TEXAS

CALLING-CARD RECEPTACLE

Application filed November 28, 1928. Serial No. 322,473.

This invention relates to a calling card receptacle for use in combination with a door lock, knocker or bell.

The main object of the invention is to provide a simple and neat pocket or receptacle in which calling cards and the like may be deposited when the person being called upon is not at home, the said pocket or receptacle being susceptible of use in combination with the door lock plate or with the door knocker or bell.

Another object is to provide a calling card receptacle for a door, the same including a door plate having a pocket formed in its upper portion for receiving calling cards, the said pocket opening upwardly, the front wall thereof being bulged outwardly to help form the pocket and being cut away at its upper margin to facilitate the removal of the cards.

With the foregoing and other objects in view the invention resides in the novel construction and arrangement of parts as hereinafter set forth and claimed:

In the drawings:

Figure 1 is a front view of a door knocker with a card receiving pocket formed therein.

Figure 2 is a section along the line 2—2 in Figure 1.

Figure 3 is a front view of a door lock having a card receiving pocket formed therein.

Figure 4 is a front view of a door bell having a card pocket formed therein.

Referring now more particularly to the drawings the reference character 1 in Figure 1 denotes a back plate of any desired construction and form which may be secured to the wall or in any convenient position upon a dwelling by means of screws (not shown) through the apertures 2. A knocker hammer or element 3 is pivotally attached at its ends to this plate 1 by means of pins 4 through the lugs 5, the aforesaid elements constituting a door knocker of the usual form.

In accordance with the invention a rectangular pocket 6, open at its upper edge, is provided in the back plate 1, the said pocket being adapted to receive calling cards and the like. The forward wall of the pocket 6 is

preferably cut away as at 7 to facilitate the removal of the cards from the pocket.

In Figure 3 the invention is shown in use with the lock plate 8 of a door lock. A card receiving pocket 9 is formed in the plate 8 in its upper portion, the front wall of this pocket being bulged outwardly as indicated and being also cut away as at 10 to facilitate the removal of cards from the pocket.

In Figure 4 the invention is shown in use upon a door bell mounting plate 11, 12 denoting the card receiving pocket formed in the said plates 11 and 13 denoting the cut away front wall of the pocket, the said front wall being bulged outwardly as indicated. The card receiving pocket may also be formed in an individual plate and secured to the dwelling in any convenient position as will be understood.

While I have herein set forth certain preferred embodiments of my invention it is understood that I may vary from the same in minor structural details, not departing from the spirit of the invention and within the scope of the appended claim.

I claim:

In a device of the kind described, a door plate having a pocket formed in its upper portion for receiving calling cards, the said pocket opening upwardly, the front wall of the said pocket being bulged outwardly and being cut away at its upper margins to facilitate the removal of the cards.

In testimony whereof I affix my signature.

NELLE EDE MONTAGUE.
